CLAIM

The ornamental design for a ring leg plant pot, as shown and described.

DESCRIPTION

FIG. 1 is a bottom perspective view of a ring leg plant pot showing my new design;

FIG. 2 is a cross-section view thereof, taken along line 2—2 of FIG. 3;

FIG. 3 is a front elevation view thereof, the right side, left side, and rear elevation views being substantially identical thereto except for the location of the unclaimed notches along the bottom;

FIG. 4 is a bottom plan view of thereof; and,

FIG. 5 is a top plan view thereof.

The broken lines depict environmental subject matter only and form no part of the claimed design.
